UNITED STATES PATENT OFFICE.

WILLIAM H. WILSEY, OF SIOUX CITY, IOWA.

SAFETY DEVICE FOR ELEVATORS.

SPECIFICATION forming part of Letters Patent No. 704,468, dated July 8, 1902.

Application filed April 12, 1902. Serial No. 102,636. (No model.)

To all whom it may concern:

Be it known that I, WILLIAM H. WILSEY, a citizen of the United States, residing at Sioux City, in the county of Woodbury and State 5 of Iowa, have invented new and useful Improvements in Safety Devices for Elevators, of which the following is a specification.

This invention relates to safety devices for elevators, it being of that kind having means 10 for preventing the well-door being opened except when the elevator-car is stopped opposite the landing upon which said well-door is located and the ascent of the car while the well-door is open for the entrance or exit of 15 passengers. Generally the space between the car and the inner wall of the well is very slight, and it is essential to avoid all projections on the car or cage on the outside thereof. In existing apparatus of this character 20 parts thereof on the car project so far from the same as to render the same impossible in many cases of successful installation.

One object of the invention is to provide a simple, inexpensive, and practical safety device for elevators which can be readily installed on all types of elevators. In the present case the parts of the appliance are 25 closed or housed by the car or cage.

The invention includes, in combination with 30 an elevator-well having an opening, a door for said opening, a latch for holding the door shut, a car, a controller on the car, a detent effective for holding the controller in a central position, and means upon the latch for 35 holding the detent in its effective position when the door is opened and the detent when in its ineffective position serving to prevent retractive movement of the latch; and the several parts may be of any suitable construction, material, or disposition, the invention 40 not being limited in these respects, although I will hereinafter describe an arrangement which is adapted for securing the desired results.

45 The invention is clearly illustrated in the accompanying drawings, forming a part of this specification, and in which—

Figure 1 is an inside face view of an elevator-car and a portion of its well, the detent being shown in its effective position. Fig. 2 is a similar view showing the detent 50 in its ineffective position. Fig. 3 is a trans-

verse sectional elevation, the section being taken in the line 3 3 of Fig. 1 and looking toward the right. Fig. 4 is a similar view, 55 the section being taken in the line 4 4, Fig. 1. Fig. 5 is a detail in plan view hereinafter more particularly described.

Like characters refer to like parts in all the figures of the drawings. 60

Referring now to the drawings, the numeral 10 indicates the well of an elevator, and 11 a car or cage adapted to travel therein. The well or casing 10 has an opening 12, adapted to be closed by the door 13, which is shown 65 as being of the sliding kind and which is held shut by the usual latch.

The car is provided with a controller 14, which is shown as a swinging or oscillating lever carried by the rock-shaft 15, suitably 70 mounted upon the car and connected with the usual operating mechanism. In Fig. 1 the controller is shown as being in its central or ineffective position or that which it occupies when stopping the car. When thrown to the 75 left or right of this position, as the case may be, the car will be caused to ascend or descend. The numeral 16 indicates a detent which is mounted upon the inside of the car and is adapted when in its effective position 80 to maintain the controller 14 in a central position in order to hold the car against movement. The detent 16 has a body of segmental form, it being provided at one end (shown at the left) with an angular projection 17, 85 through which the pivot-screw 18 is adapted to extend. Such screw also passes through one end of the segmental guide-plate 19, while a similar screw 20 passes through the opposite end of said guide-plate, the two 90 screws serving to hold such plate in place. The screws also pass through the ends of a similar plate 21 in parallelism with the other plate, and the controlling-lever 14 is adapted to oscillate between such plates. 95

The segmental body of the detent 16 has on its under side the notch 22, the walls of which are beveled and converge toward the upper side of the detent. When the lever 14 is thrown to its central or ineffective position, 100 the detent 16 can be lowered, so as to bring the notch 22 over the outward projection 23 upon the controller or lever 14, in which position it will be positively held by means upon

a latch hereinafter described, which is adapted to hold the door 13 shut. While I may rely upon gravity to secure the movement of the detent 16 into its effective position, I prefer in order to secure quick action thereof to employ a spring 24. The spring 24 is an elongated one, it being secured at its lower end to the car interiorly the same and its free end bearing against the detent 16 just 10 above the pivot of the latter, so that when the controller is swung to its central position the spring will instantly shift the detent into its effective position.

The door 13 is provided at a suitable height 15 with a ledge 25, extending entirely across the same, said ledge being horizontally disposed and having a vertical web suitably secured to the inside face of said door.

To the outer side of the car 11, at a suitable point—say near the floor thereof—I secure the lower end of the latch 26, the latter consisting in the present case of a flat spring. The latch 26, which, it will be seen, is yieldable, is adapted when the car is immediately 25 above or below the floor or landing to be disposed in the path of the ledge 25, which constitutes a suitable catch, so as to arrest the movement of the door when an attempt is made to open the same. When, however, 30 the controller is brought to a central position in order to stop the car or cage at the floor or landing, the latch can be retracted and the door can be opened, and as it is opened the ledge or catch 25 by bearing against the said latch at or near its free end will maintain the 35 same in its position to lock the detent 16 in position to maintain the controller in its central position.

The segmental or arcuate body has at or 40 near its free end the perforation or hole 27, adapted when said detent is in its effective position to register with a similar hole or perforation 28, extending through the wall of the car. The latch 26 has at its upper end the 45 lug or pin 29. It will be understood that when the car is moving up or down in its well the detent 16 will be in its elevated position, as shown in Fig. 2, so that if an attempt be made to open the door the latter when it 50 moves a trifling distance will retract or force back the spring-latch 26 or until the pin or lug 29 strikes the solid part of the detent 16 either above or below the perforation 27, so that practically no movement of the door in 55 a direction to open the same can be accomplished. When, however, the elevator-car is stopped, (and it will be necessary to bring the controller 14 into a central or vertical position in order to do this,) the holes 27 and 60 28 will be caused to register, so that the door can be opened all the way, and as it opens the spring-latch is forced backward and the pin or lug 29 thereon is caused to enter the perforation 27, thereby preventing the detent 16 65 from moving, and this relation will be prolonged while the door is open, it being understood that the ledge 25 is in contact with the

free end of the spring-latch. When, however, the door is closed, the latch will automatically move into position to again arrest the opening of the door, and as it does so the pin or lug 29 will be carried out of the perforation 27, so that the detent can be lifted. When the pin releases the detent, the controller 14 can be swung either to the right or to the left, 75 and as it does so the projection 23 thereon will ride along one or the other of the inclined faces of the notch 22, so as to lift said detent or to put it into position to prevent retractive movement of the latch 26. The car 80 carries on the inside thereof the bracket 30, suitably secured thereto, and which overhangs and is in contact with or substantially in contact with the free end of the detent, so as to hold said detent solid when the pin or 85 lug 29 is forced against the imperforate portion of the same.

What is shown as the inner end of the ledge or catch 25 is shown as beveled at 35, and the beveled face 35 is adapted when the holes 27 and 28 are brought into registration, as herein-before set forth, to ride along the spring-latch 26, so as to force said latch rearward and cause the pin 29 to enter said registering openings, such beveled face being shown in Fig. 5. 95

Having described the invention, what I claim is—

1. The combination of an elevator-well having an opening, a door for said opening, a latch for holding the door shut, a car, a controller on the car, a detent operative independently of said controller and effective for holding the controller in a central position, and means upon the latch for holding the detent in its effective position when the door is opened, and the detent, when in its ineffective position serving to prevent retractive movement of the latch.

2. The combination of an elevator-well having an opening, a door for said opening, a latch for holding the door shut, a car, a controller on the car, a detent operative independently of said controller and effective for holding the controller in a central position and having a perforation, and a pin upon the latch adapted to enter said perforation when the detent is in its effective position.

3. The combination of an elevator-well having an opening, a door for said opening, a latch for holding the door shut, a car, a controller on the car, having a projection, a notched detent, the notch of which is adapted to engage over the projection on the controller, and said detent having a perforation, and a pin upon the latch adapted to enter said perforation.

4. The combination of an elevator-well having an opening, a door for said opening, a spring-latch for holding the door shut, a car, a controller on the car, a detent operative independently of said controller and effective for holding the controller in a central position, and means upon the latch for holding the detent in its effective position when the

door is open, and the detent when in its ineffective position serving to prevent retractive movement of the latch.

5. The combination of an elevator-well having an opening, a door for said opening, a latch for holding the door shut, a car, a controller on the car, a detent operative independently of said controller and effective for holding the controller in a central position, means upon 10 the latch for holding the detent in its effective position when the door is opened, and the detent when in its ineffective position serving to prevent retractive movement of the latch, and means upon the door for holding said latch in its retracted position while the door is open.

6. The combination of an elevator-well having an opening, a door for said opening, a ledge extending entirely across the door, a latch disposed in the path of the ledge, a car, a controller on the car, a detent operative independently of said controller and effective for holding the controller in a central position, and means upon the latch for holding the detent in its effective position when the door is open and the detent, when in its ineffective position, serving to prevent retractive movement of the latch, and said ledge, when the door is open, being adapted to hold the latch 25 in its retracted position.

7. The combination of an elevator-well having an opening, a door for said opening, a detent for holding the door shut, a car, a controller on the car, a pivoted latch operative 30 independently of said controller and effective

for holding the controller in a central position, and means upon the latch for holding the detent in its effective position when the door is open, and the detent, when in its ineffective position, serving to prevent retract- 40ive movement of the latch.

8. The combination of an elevator-well having an opening, a door for said opening, a detent for holding the door shut, a car, a controller on the car, a pivoted latch operative 45 independently of said controller and effective for holding the controller in a central position, means upon the latch for holding the detent in its effective position when the door is open, and the detent, when in its ineffective 50 position, serving to prevent retractive movement of the latch, and a bracket upon the car contiguous to the free end of the detent.

9. The combination of an elevator-well having an opening, a door for said opening, a latch 55 for holding the door shut, a car, a controller on the car, having a projection, a detent having a notch to engage over said projection and a perforation, a pin upon the latch adapted to enter said perforation, and a ledge extending across the door, the latch being disposed in the path of the ledge.

In testimony whereof I have hereunto set my hand in presence of two subscribing witnesses.

WILLIAM H. WILSEY.
